UNITED STATES PATENT OFFICE.

RAOUL GARNEAU, OF QUEBEC, QUEBEC, CANADA.

GAS BURNER.

Application filed March 1, 1926. Serial No. 91,580.

The present invention pertains to a novel gas burner designed for the combustion of a mixture of gas and air.

The principal object of the invention is 5 the provision of a device of this character in which the air under pressure is mixed with the gas in order to obtain an intense flame with a small consumption of gas.

This burner is employed particularly for 10 heating boilers used in tailoring establishments for the pressing of clothing under steam. In the accomplishment of the objects of the invention, the burner is placed beneath the water compartment of a simple 15 boiler. The burner itself comprises a hollow base in which is mounted a circular partition dividing the interior of the base substantially into two sections. The partition is however interrupted to permit communication 20 between the two sections. Gas and compressed air are emitted to the outer section, and a complete mixture is made by the circulation of the gas and air from one side of the partition to the other. A number of 25 jets are inserted in the top wall of the base and are evenly distributed on both sides of the partition. The intimate mixture which has been formed in the manner indicated is ignited at the uniformly distributed jets 30 whereby a corresponding number of effectively arranged flames are produced.

The invention is fully disclosed in the following description and in the accompanying drawings in which:—

35 Figure 1 is a fragmentary vertical section of a boiler showing the burner installed therein;

Figure 2 is a plan view of the burner;

40 Figure 3 is a plan view, partly in section, of the burner;

Figure 4 is a diametrical section of the burner;

Figure 5 is a detail section;

45 Figure 6 is a plan view of one of the jets; and

Figure 7 is a sectional view of the union for connecting the gas and compressed air pipes to the burner.

Reference to these views will now be made 50 by use of like characters which are employed to designate corresponding parts throughout.

The burner comprises a hollow body or base 1 having a central opening 2 which 55 renders the inner space of the base annular in formation. This space contains a circular

partition 3 extending from the bottom wall 4 to the top wall 5, as shown in Figure 4, and interrupted as at 6 and 7 to permit flow between the spaces at opposite sides of the 60 partition.

Into the top wall 5 are threaded a number of jets 8 divided into two circular series disposed at both sides of the partition 3. The elements of the inner series alternate 65 with those of the outer series as clearly shown in Figure 2.

Each jet 8 is a substantially tubular member having a rounded upper end 9 and a pair of intersecting slots 10 formed in the rounded end as illustrated in Figure 6.

At one side of the base 1 is formed a nipple 11 into which is inserted a connecting pipe 12 received in one of the arms 13 of a 3-armed union 14. The remaining openings 75 15 and 16 of the union receive a gas pipe 17 and a compressed air pipe 18 respectively as shown in Figure 3. A nozzle 19 is disposed within the union and has branches 20 and 21 which extend to the arms 15 and 16 respectively. The outlet of the nozzle is of smaller cross section than the fluid pipes 17 and 18 as is also evident from Figure 7. The pipes 17 and 18 are provided with valves 22 and 23 respectively by means of which the 80 delivery of fluid to the nozzle may be controlled.

Figure 1 illustrates the burner installed in a simple boiler 30 having a transverse partition 31 which forms a water compartment 32 and a fire pot 33. The base 34 of the boiler has an opening 35 for the additional supply of air.

In the operation of the burner, gas is admitted through the pipe 17, and the compressed air which enters through pipe 18 aids in carrying the gas to the body of the burner. The gas and air are mixed, and the product is distributed to each of the jets 8, assuring a uniform and regular combustion beneath the water space 32. This is obtained by the interrupted wall 3 which finally mixes the air and gas in a thorough manner, and by the peculiar positioning of the jets 8 as described above. It will be 95 apparent that the burner itself constitutes a means for completing the mixing operation which commences as the gas and air pass from the relatively narrow nozzle 19 into the pipe 12.

100 While a specific embodiment of the invention has been illustrated and described,

it is to be understood that various alterations in the details of construction may be made without departing from the spirit of the invention as indicated by the appended claims.

Having thus fully described the invention, what I claim as new and desire to protect by Letters Patent is:—

- 10 1. A gas burner comprising a hollow base, a plurality of jets inserted therein, each jet having a pair of intersecting slots in its outlet end, a circular interrupted partition within said base, a union having three openings, a pipe connecting one of said openings with said base, gas and air pipes connected to the remaining
- 15 2. A gas burner comprising a hollow base, a plurality of jets inserted therein, a circular interrupted partition within said base, a union having three openings, a pipe connecting one of said openings with said base, gas and air pipes connected to the remaining
- 20

openings, a nozzle within said union and having branches leading to the gas and air openings, the outlet of said nozzle being of smaller diameter than said pipe.

3. A gas burner comprising a hollow base, 25 a plurality of jets inserted therein, each jet having a pair of intersecting slots in its outlet end, a circular interrupted partition within said base, a union having three openings, a pipe connecting one of said openings with said base, gas and air pipes connected to the remaining 30 openings, a nozzle within said union and having branches leading to the gas and air openings, the outlet of said nozzle being of smaller diameter than said 35 pipe.

In witness whereof I have hereunto set my hand.

RAOUL GARNEAU.
